UNITED STATES PATENT OFFICE.

LA VERNE W. NOYES, OF CHICAGO, ILLINOIS.

CROSS-ARM FOR TOWERS.

No. 857,101.

Specification of Letters Patent.

Patented June 18, 1907.

Application filed July 2, 1906. Serial No. 324,439.

To all whom it may concern:

Be it known that I, LA VERNE W. NOYES, a citizen of the United States, residing at Chicago, in the county of Cook and State of Illinois, have invented new and useful Improvements in Cross-Arms for Towers, of which the following is a full, clear, concise, and exact description, reference being had to the accompanying drawing, forming a part of this specification.

My invention relates to improvements in towers and particularly to towers used for electrical transmission lines, my object being to provide a tower having suitable means for carrying the electrical transmission wires.

Other features of my invention will appear in the specification and appended claims.

I have illustrated my invention in the drawings forming a part of this specification, and in which

Figure 1 is a side elevation of the upper portion of my tower; Fig. 2 is a sectional view taken on the line 2—2 of Fig. 1; Fig. 3 is a sectional view taken on line 3—3 of Fig. 2; and, Fig. 4 is a sectional view taken on the line 4—4 of Fig. 3.

In the preferred embodiment of my invention the post of my tower is preferably formed of a plurality of converging angle irons or legs. This post may be the single post of a three-leg tower, in which the angle irons 1, 2 and 3 are continued and form the legs of the tower, or this post may be one of a plurality of posts formed on a suitable base of any character. The converging legs 1, 2 and 3 of the posts are preferably interlaced at their converging point and are bound together by suitable clamps 4 and 5. Suitable braces 6 are arranged at intervals along the legs which properly brace the same, and tie the same together into a unitary structure. At the point of convergence of the legs 1, 2 and 3, formed of angle irons, a socket is formed, into which are arranged to be fitted a pair of socket-pieces 7 and 8. These socket-pieces have their outer sides formed to conform to the shape of the socket formed by the converging ends of the legs 1, 2 and 3 and have on their inner faces semi-circular recesses 9, in which are adapted to fit a portion of the cross-arm 10 and a portion of the vertical arm 11. This vertical arm is preferably formed of angle iron, having its upper end flattened as at 12, to receive a wire and its lower end rounded to form a semi-circular portion 13, arranged to fit in the socket

formed by the recesses 9 in the blocks 7 and 8, and around the cross-arm 10. The cross-arm is of peculiar formation and is preferably formed of iron pipe having an intermediate vertical portion 14, which is clamped between the blocks 7 and 8, and substantially horizontal end-portions 15 and 16, which support at their outer ends insulators 17 and 18. These insulators may be supported in any desired manner and are here shown as being supported upon suitable vertical posts 19 and 20, which are bolted in openings formed in the ends 15 and 16. At a lower point on the tower, a second cross-arm 21 is also secured which, like the cross-arm 10, is formed of iron pipe and has its inner end flattened and bolted to the legs 3 of the post of the tower. An intermediate portion of the cross-arm 21 rests upon and is secured to one of the horizontal braces 6 of the tower, being secured in position by a strap or staple 22, which has its opposite ends passing through openings in the brace 6, and provided with bolts 23, to secure the same in position. The outer end of the cross-arm 21 also carries an insulator pin 24, which is secured upon a vertical post 25, in the same manner as the insulator pin 17.

Having thus described my invention what I claim as new and desire to secure by Letters Patent is:

1. The combination with the post of a tower, of a cross-arm therefor having a portion by which it is supported substantially at right angles to the remainder thereof, and a second arm having one end connected to one leg of the post and an intermediate portion secured to and supported by one of the braces of the tower.

2. The combination with the post of a tower, of a hollow cylindrical cross-arm therefor having one portion thereof connected to one leg of the tower, and an intermediate portion supported by and secured to one of the braces of the post.

3. The combination with the post of a tower, of a cross-arm therefor having a substantially vertical intermediate portion by which it is supported in position, and substantially horizontal end-portions.

4. The combination with the post of a tower, of a cross-arm therefor having an intermediate portion by which it is supported extending substantially at right angles to its end-portions.

5. The combination with the post of a

2

tower, of a cross-arm therefor, cylindrical in cross section and having an intermediate portion by which it is supported extending substantially at right angles to the end-positions.

5 6. The combination with a plurality of converging legs of the post of a tower, of a cross-arm for the tower having a portion thereof clamped between said posts.

10 7. The combination with a plurality of converging posts of a tower, of a cross-arm therefor having a portion thereof clamped

between said posts at the point where they converge and extending substantially at right angles to the remaining portion of the 15 arm.

In witness whereof, I have hereunto subscribed my name in the presence of two witnesses.

LA VERNE W. NOYES.
